UNITED STATES PATENT OFFICE.

SIMON DOKK OLSEN, OF WEST HAM, LONDON, ENGLAND, ASSIGNOR TO THE OLSEN ENGINE SYNDICATE LIMITED, OF LONDON, ENGLAND, A BRITISH COMPANY.

MOTIVE-POWER ENGINE.

Application filed August 27, 1921. Serial No. 495,862.

To all whom it may concern:

Be it known that I, SIMON DOKK OLSEN, a subject of the King of Norway, residing at 41 Meath Road, West Ham, E. 15, in the 5 county of London, England, have invented certain new and useful Improvements in or Relating to Motive-Power Engines, of which the following is a specification.

This invention has reference to motive 10 power engines, and relates more particularly to engines of the type having cams for converting the reciprocating motion into rotary motion, instead of the ordinary crank arrangement.

15 The invention, which is applicable both in connection with internal combustion engines and with steam or compressed air engines, is designed to provide an arrangement such that the stresses or strains set up in the 20 working strokes are balanced or counteract each other.

A feature of the invention is that the cam 25 is in the form of a hollow cylinder, shell or drum made wide on one side and narrow on the opposite side, its edges sloping equally in opposite directions or converging towards the narrow part or side. These edges form 30 cam tracks against which the opposing pistons act practically direct through the medium of rollers or trucks instead of requiring piston rods or connecting rods.

Another feature of the invention is that 35 it enables several working cylinders to be arranged parallel around the main shaft in circular co-axial groups or sets, thus securing great compactness relatively to the power of the engine. Two or more such groups may also be arranged concentrically one inside the other.

40 A further feature of the invention is that the cam which serves to convert the motion, may be arranged between the pistons in such a way that they act on opposite sides of it and counterbalance one another, the cam being 45 thus practically free from endwise, lateral or twisting strains.

The distributing valves are controlled from a single cam.

According to the invention, two groups of 50 cylinders are arranged opposite each other, so that the cylinders form opposing and co-axial pairs and corresponding cylinders act simultaneously or synchronously. The main shaft extends centrally through the two groups and on it the cam arrangement is se-

cured between the said cylinder groups. The piston of each cylinder carries a roller or truck which abuts against the edge of the cam and transmits the pressure thereto practically direct. In the case of a two-stroke 60 internal combustion engine for instance scavenging air or motive fluid may be supplied through annular chambers or boxes arranged in the centre of each group of cylinders, these boxes having axial sleeves or 65 passages extending through them to hold the bearings of the main shaft.

In order that the invention may be clearly understood and readily carried into effect reference will now be had by way of example to the accompanying diagrammatic drawings, in which:

Fig. 1 is a longitudinal or axial section of an engine comprising two groups of six cylinders with a cylindrical cam between them. 75

Fig. 2 is an end view of one group of cylinders, the right-hand half being in transverse section through the exhaust ports of the cylinders.

Fig. 3 shows a development of the cam 80 paths formed by the opposite edges of the cam cylinder.

In these drawings:

a *a* are the cylinders, which are provided with hollow pistons *b* carrying rollers *c* for 85 transmitting the thrust or pressure. These cylinders are disposed around the main shaft *d* to which is keyed the cylindrical or drum cam *e* whereby the pistons produce rotation of the shaft.

In the arrangement shown, the cylinders are mounted in two castings *f* each carrying a group or nest of six cylinders *a* disposed around it evenly and parallel with the shaft *d*. The said castings are fitted or bolted together in the middle by their flanges *g* to form the main or outer casing of the engine.

Inside each cylinder group is a hollow annular chamber or distributing box *h* (for the scavenging air or motive fluid according 100 to the type of engine) and through the hollow centre of these two boxes, extend adjustable bearings or brasses *i* for the aforesaid main shaft *d*.

The cylinders themselves may as shown 105 be fitted into the casing from each end, suitable spaces or jackets *j* being left around said cylinders. Being in alignment the cylinders can easily be bored out when in position.

- The adjacent or opposing ends of the cylinders come close together but are slotted longitudinally as at a^1 , sufficiently to accommodate or clear the widest part of the shell 5 of the cylindrical or drum cam e , over or beyond which they extend, or rather which projects into the adjacent ends or mouths of the cylinders. This cam or drum e is wide at one side and narrow at the other, its edges 10 tapering or converging as in Fig. 1, so that it is wedge-like or V-shaped. It thus corresponds to only one to-and-fro stroke of the pistons for each revolution, and ensures very smooth running even at high speeds.
- 15 The said cam also has a web or disc e^1 with its nave or hub e^2 secured on the main shaft, and the hub may be thickened considerably as at e^3 on the side where the cam itself is narrow, to act as a counterweight 20 for the purpose of securing properly balanced rotation.

The width of the widest and narrowest parts of the cam depends on circumstances, the main point being to secure a convenient 25 angle of slope or inclination for the converging edges e^4 . In the example shown the greatest width (that at the top of Fig. 1) is rather more than one and one half times the radius of the cam drum, and this has been 30 found a convenient size in practice. The opposite or narrow edge is approximately the width of the central disc e^1 only. Of course these proportions may be considerably altered in practice and are only given as 35 illustrations.

To prevent the pistons turning on their axes, they may each be provided with a pin working in a groove in the cylinder in the well known manner.

40 The exhaust k of all the cylinders of each group are connected together by pipes k^1 surrounding the engine, and such pipes may discharge into a common main exhaust k^2 .

45 l are openings which may be provided (as hereinafter referred to) for admitting scavenging air in an internal combustion engine.

In such a case the narrow part of the cam is suitably shaped to allow sufficient time 50 for the discharge of the spent gases and the admission of scavenging air.

The outer or end covers a^2 of the opposite cylinders are provided with lugs m for tie-bolts m^1 extending from side to side or end to end of the main casing, and serving to 55 hold or tie the whole structure together.

The pistons b may be of the usual trunk type used in explosion motors, but in the mouth of each is arranged diametrically a pin or short axle c^1 on which is mounted the 60 truck or roller c for transmitting the power to the drum cam and these rollers press constantly against the cam edges e^4 .

The edges of the roller and cam may be bevelled as shown (somewhat like bevel-gearing) to ensure proper running, and

those of the cam may be flanged outside to assist in keeping the rollers in position. In fact the edges of the cam serve, in effect, as flanged rails for the rollers to run on as the cam e revolves under the inward pressure of 70 the pistons b and rollers c against the sloping or cam-like edges e^4 . In other words the rollers c of the two pistons at the top of Fig. 1 press on the widest part of the cam (compare middle of Fig. 3) and force 75 it away from between them, so revolving the cam and the shaft d .

The same action occurs as the widest part of the cam passes between each pair of pistons and rollers c (see Fig. 3), the working 80 strokes or explosions being suitably timed to take place at that instant. Since the thrust of one piston is opposite to that of its fellow piston in the other group, they counteract each other and a practically perfect balance 85 is obtained.

The lower pair of pistons in Fig. 1 have finished their working stroke and are about to be forced back in the same position as those at the top, as the widest part of the 90 revolving cam comes down between them. As soon as this part has just got past them, they will again perform a working (or explosion) stroke and impart a further impulse to the cam, and so on. 95

In the arrangement illustrated, the timing and ignition are controlled electrically by a commutator barrel n on the shaft d co-operating with brushes o . This barrel is adapted to be moved endwise and is provided with a shifting lever p (having a pin and groove connection therewith of the usual kind) whereby its position relatively to the brushes can be altered and thus the engine can be stopped by sliding the barrel n to such a position that its contacts miss the brushes o . The invention is not however confined to such a timing and ignition system. 100

The tapered brasses or bearings i for the main shaft d are also adjustable endwise 110 to take up wear, this adjustment being effected by means of nuts i^1 on screws i^2 secured in the main casing.

A special advantage of the construction above set forth is that the pistons can be 115 very easily taken out, since there are no actual connections between the piston and the cam which require to be unmade. In fact it is only necessary to take off the back or end cover and any of the pistons can be drawn 120 out immediately.

The invention is particularly applicable to two-stroke Diesel engines, in which case the exhaust can go into the central chamber f^1 in which the cam revolves, and pass out 125 through the annular box-like frame or casing h between the cylinders which would act as a silencer.

Obviously the invention may be modified in various ways in carrying the same in- 130

to practice without departing from the general nature thereof.

I claim:—

1. The combination of a cylindrical cam made wide at one side and narrow at the opposite side with converging edges, opposed cylinders and pistons arranged in circular groups at either side of said cam, the two groups lying close together with the cylinder mouths overlapping the cam edges, and opposite cylinders being separated only by the web of the cam, substantially as described.
2. The combination of a cylindrical cam wide at one side and narrow at the opposite opposed cylinders and pistons arranged in circular groups at either side thereof with slots at their adjacent ends to allow them to overlap the cam so as to properly guide the piston, and a casing formed in two halves each half containing one of the cylinder groups, substantially as described.
3. The combination of a shaft carrying a V-shaped cam wire at one side and narrow at the opposite, slotted cylinders on opposite sides of said cam arranged parallel with the shaft in opposed circular groups and overlapping the cams so as to guide their pistons, a casing into which the cylinders of each group are fitted, pistons inside said cylinders, rollers mounted in the mouths of the pistons and acting on the opposite edges of the cam, means for causing opposite pistons to perform their working strokes simultaneously counter to each other so that each neutralizes the strain due to the other, and detachable covers at the outer ends of the cylinders to permit the easy withdrawal of the pistons, substantially as described.
4. The combination of a shaft carrying a V-shaped cam, wide at one side and narrow at the opposite, opposed cylinders on opposite sides of said cam overlapping the same in order to support and guide their pistons, and arranged parallel with the shaft in

circular groups, a casing divided in the middle and having the cylinders of each group arranged in one half thereof, pistons inside said cylinders acting counter to each other, rollers carried by said pistons acting on the opposite edges of the cam and tie-rods extending between the end covers of the corresponding opposed cylinders, substantially as described.

5. The combination of two circular groups of opposed cylinders and pistons with corresponding pistons acting counter to each other, a cylindrical cam arranged between said groups, and made wide at one side and narrow at the other, rollers carried by said pistons acting against the edges of the cam, a central web by which said cam is carried, slotted mouths at the adjacent ends of the cylinders to permit of their coming close up to the web of the cam, a shaft parallel with the cylinders, and an outer casing divided in the middle and having a group of cylinders in each half thereof, substantially as described.

6. The combination of two circular groups of opposed cylinders and pistons acting counter to each other, a cylindrical cam arranged between said groups with the mouths of the cylinders overlapping same so as to come close to the web of the cam and afford guidance for the pistons and support against lateral pressure, rollers in the mouths of the pistons acting against the lateral edges of the cam, a shaft parallel with the cylinders, an outer casing for each cylinder group in which the said cylinders are fitted, bearings for the shaft arranged at the centre of each casing, and means for tying the casings together all round so that all the strains are self-contained and neutralise each other, substantially as described.

In testimony whereof I affix my signature.

SIMON DOKK OLSEN
